UNITED STATES PATENT OFFICE.

JOSEPH W. SCHOENDELEN, OF OGDEN, UTAH, ASSIGNOR TO AMERICAN CAN COMPANY, OF NEW YORK, N. Y., A CORPORATION OF NEW JERSEY.

COMBINED PRESS AND WASTE-REMOVING SLITTER.

Application filed November 19, 1923. Serial No. 675,458.

To all whom it may concern:

Be it known that I, JOSEPH W. SCHOENDELEN, a citizen of the United States, residing in Ogden, in the county of Weber and 5 State of Utah, have invented a new and useful Improvement in Combined Presses and Waste-Removing Slitters, of which the following is a specification.

The present invention relates to machinery 10 for cutting sheets of tin plate, or the like, to obtain pieces of proper size and form for particular uses, such, for example, as the making of can ends.

In order to obtain a maximum number of 15 cuts from a sheet of given size, it has become the practice to cut circular pieces from the sheets in accordance with what is known as a stagger lay-out, i. e., by cutting the pieces in rows with the cuts of adjacent rows 20 out of alignment. This obviously permits the rows to be arranged closer together than would be possible with the so-called straight cut, due to the rounded lines of the cut.

In order to thus minimize the wastage, 25 particularly when relatively large disks are being cut, the sheet must be quite large, so as to permit the staggered cuts, which, of course, would be impossible with a narrow strip, such as might be used in straight cutting, or when relatively small disks are desired.

Customarily, a central row of cuts are first made in the sheet and thereafter the side cuts are made, this necessitating considerable 35 handling of said sheets before the full number of cuts are made. After the central cuts have been obtained, the sheet is very limber and extremely difficult to handle, it being impossible to automatically pass such 40 a sheet through the feeding mechanism of the press. Consequently, it has been found necessary to position said sheet for the later cuts by hand, or to transfer the sheet by hand from the press and to sever it along a 45 median line to produce separate sheet portions which might be mechanically fed into the press.

The purpose of the present invention is to 50 overcome the difficulties just described by automatically transferring the sheet from the press, after the central row of cuts has been made, and removing the flimsy scrap portions between the cuts of said central row, thus providing two rigid sheet portions 55 which can be handled by the automatic feed-

ing devices of the presses while the remaining cuts are being made.

Other objects and advantages of the invention will be apparent as it is better understood from the following description, which, 60 taken in connection with the accompanying drawings, discloses a preferred embodiment thereof.

Referring to the drawings,

Figure 1 is a side elevation, partially in 65 section and largely diagrammatic, of a machine assembly constructed in accordance with my invention;

Fig. 2 in a top plan and partially sectional view thereof, being taken substantially along 70 the broken line 2—2 in Fig. 1; and

Fig. 3 is a plan view of a sheet of tin plate such as is adapted to be acted upon by the mechanism of my invention, showing the 75 staggered lay-out of the cuts.

Considering said drawings in detail, it will be noted that a press frame 11 is supported from a base 12 and provides bearings at the top for a shaft 13, which is driven through the medium of a pulley 14 and has 80 mounted thereon a brake mechanism 15 and a crosshead 16, which latter carries an upper slide 17 in which is positioned a punch 18.

A bed plate 19 is supported from the frame and has secured to the upper side 85 thereof a bolster plate 21, upon which is mounted a die block 22 in which is positioned a lower die plate (not shown) adapted to cooperate with the punch 18 in the cutting of the disks from the metal sheets. A feeding table 23 is supported at one end upon a bracket 24 extending upwardly from the forward part of the frame and at the opposite end by a web 25, which extends between 90 the sides members of said frame. 95

The sheets 26 are positioned upon the feeding table 23 by hand and assume a proper position for the first cut to be taken therefrom, this position being determined by means of a side guide 27 and a feeding 100 block 28, there being several of said blocks arranged along the lower length of the table at such distance apart as the cuts of a row are to be spaced.

The above described machine is or may 105 be of the construction shown in my other application Serial No. 679,459 filed of even date herewith.

After the proper number of cuts have been 110 made in the central row, the sheet is deliv-

ered by gravity onto a conveyer 29, a deflecting plate 31 being provided at the lower end of the table 23 to cause said sheet to be properly positioned upon said conveyer 5 which is inclined upwardly from the bottom of said table 23. The conveyer 29 is directed about a drum 32 mounted on a shaft 33, which has bearings 34 positioned upon the base members 12, and about a drum 10 35 on a shaft 36, which is bearing in a bed portion 37 of a slitting machine which is supported by a frame, generally indicated by the reference character 38. A supporting plate 39 extends beneath the conveyer 29 and connects said press and slitting machine, the ends of said plate resting upon brackets 41 and 42 provided respectively upon the two machines.

The conveyer is driven by means of a 20 sprocket chain 43, taking over a sprocket mounted on the end of the shaft 36 and over a similar sprocket on a shaft 44, which has bearings at the upper end of a table 45 of the slitting machine and carries a pulley 25 46 by which it is driven from any suitable source of power.

A feeding roller 47 is mounted on an idle shaft 48 above the conveyer drum 35 and is rotated by the latter to hold the sheet 30 26 to the conveyer as it is directed therefrom onto the table 45 of the slitting machine.

35 Rotary slitter knives 49 and 51 are mounted respectively on the drive shaft 44 and an upper shaft 52, which is mounted above and in parallel relationship to said shaft 44, said shafts being geared together by means of gears 53 and 54 mounted respectively thereon.

40 As the sheets are fed to said slitter knives, they pass between side guides 55 and 56, the latter having on its inner side leaf springs 57 bearing against the edge of the sheet and holding it against the opposite guide 55. Retaining plates 58 and 59 are employed to prevent any upward displacement of the sheet from the table.

45 It will be noted that there are two each of the knives 49 and 51 and that these are spaced apart a sufficient distance to remove scrap portions 61 between the circular cuts 62, which, as noted before, are arranged in a row at the center of the sheet. This produces two separate sheets 63 and 64, which are sufficiently rigid to be subsequently passed through the automatic feeding mechanism of the presses, with the result that the difficulty of handling a large sheet, rendered limber and unwieldy by the narrow connecting webs which constitute the waste 55 portions 61, is eliminated.

60 After the slitting operation, the sheet portions 63 and 64 and the scrap, or waste portions, 61 fall into a suitable discharge hopper 65 by which they may be directed 65 to a suitable place of deposit.

65 It is thought that the invention and many of its attendant advantages will be understood from the foregoing description, and it will be apparent that various changes may 70 be made in the form, construction and arrangement of the parts without departing from the spirit and scope of the invention, or sacrificing all of its material advantages, the form hereinbefore described being 75 merely a preferred embodiment thereof.

I claim:

1. The combination of a press adapted to cut circular articles from metal sheets, and sheet metal cutting means for cutting 80 out scrap portions from the intermediate part of said sheets to make the separated parts of the sheets practicable for handling, and mechanism operating said press and said cutting means in timed relation. 85

2. The combination of a press for removing circular articles from metal sheets so as to leave considerable areas of metal at either side of the median parts of the sheets, slitting devices arranged at a distance from each other for cutting through the scrap portions of the sheet so as to remove small scrap and leave the separated side portions of the sheet practicable for further handling, and mechanism operating said press and slitting 95 devices in timed relation. 90

3. The combination of a punch press for removing pieces of sheet metal from the median part of the sheet, slitting devices spaced apart from each other for cutting 100 out waste portions from the median part of the sheet to facilitate the subsequent handling of the separated side portions of the sheet, means for transferring said sheets from the press and through the slitting devices, and mechanism operating the press, the slitting devices and the transferring means in timed relation. 105

4. The combination of a punch press adapted to remove pieces of metal from the 110 central portion of a metal sheet and to thereby leave waste portions of metal connecting the two side portions of the sheet, slitting means for cutting out said remaining pieces of waste metal so as to leave the side portions of the sheet practicable for further handling, a conveyor for transferring the sheets from said press to said slitting means, and mechanism operating said press and slitting means and conveyor in 115 120 timed relation.

JOSEPH W. SCHOENDELEN.
